UNITED STATES PATENT OFFICE.

HARRY S. WILLIAMS, OF SAN ANTONIO, TEXAS, ASSIGNOR OF ONE-HALF TO OTTO KELLER, OF SAN ANTONIO, TEXAS.

AIR-CUSHION TIRE.

1,334,204.

Specification of Letters Patent. Patented Mar. 16, 1920.

Application filed July 18, 1918. Serial No. 311,807.

To all whom it may concern:

Be it known that I, HARRY S. WILLIAMS, a citizen of the United States, residing at San Antonio, in the county of Bexar and State of Texas, have invented certain new and useful Improvements in Air-Cushion Tires; and I do declare the following to be a full, clear, and exact description of the invention, such as will enable others skilled in the art to which it appertains to make and use the same.

This invention relates to resilient tires, and it relates more specifically to an improved air-cushion tire.

One object of this invention is to generally improve devices of this character by providing an improved structure which is exceedingly convenient, effective and durable, and which can be manufactured at a relatively low cost.

Other objects and advantages may become apparent to persons who read the following details of description in connection with the accompanying drawings, in which:

Figure 1 is a fragmental view partly in side elevation and partly in section, the sections being taken in different planes which intersect the axis of rotation at right angles.

Fig. 2 is an enlarged sectional detail view, the section being taken substantially along the line 2—2 of Fig. 1.

Fig. 3 is a detail view illustrating a fragment of a filler member of slightly modified construction.

Fig. 4 is a view similar to Fig. 1, but illustrating a modified form of the invention.

Fig. 5 is an enlarged sectional view, the section being taken substantially along the line 5—5 of Fig. 4.

Fig. 6 is a sectional detail view illustrating a fragment of the filler member of the construction shown in Figs. 4 and 5, the section being taken along the lines 6—6 of Figs. 4 and 5.

Referring to these drawings in detail, in which similar reference characters correspond with similar parts throughout the several views, and in which the wheel spokes and rim are illustrated merely for the sake of showing the relation of the tire to the wheel,—

The invention, as disclosed in Figs. 1, 2 and 3, comprises a flexible casing 1 of any appropriate kind, a resilient filler member 2 and a series of resilient cushioning mem-

bers or balls 3. The balls 3 may be of rubber or other flexible and impervious material, and the cavity of each ball may be filled with compressed air or other elastic fluid.

The filler member 2 is preferably formed of rubber, although it may be composed of any appropriate resilient or flexible material. The filler member 2 is formed with an annular series of alternate spherical recesses or chambers 4 and partitions 5, and the opposite upright walls or sides of each cavity 4 are formed with slits 6 which cross one another substantially at right angles, these slits communicating with the interior and exterior of the cavities so as to form juxtaposed tongues 7 which combine to normally close the opening through which a ball or spherical member 3 may be inserted and removed. It will be understood that any appropriate means (not shown) may be employed for spreading the tongues 7, and it should also be understood that the wall of the cavity 4 may be expanded sufficiently to permit the balls 3 to enter. When the tongues 7 are released, they return to their normally juxtaposed relation by their inherent resiliency or elasticity.

From the foregoing description, it will be seen that after the balls 3 have been inserted and the tongues 7 have returned to their normal position, the surface of the filler 2 is smooth and unbroken, so that it fits snugly within the casing 1, and the tongues 7 are held by the casing in their normal juxtaposed relation.

Referring to the modified form of filler member 2' shown in Fig. 3, it will be seen that the ends of the tongues 7 are concaved, or in other words, an opening 8 is formed between the free ends of the tongues 7 so that the spreading tool may be easily inserted between these tongues.

Referring to the modified form shown in Figs. 4, 5 and 6, the casing 10 and filler 11 are united throughout their major extent, that is, from the tread portion to the outer ends 12 of a series of slits 13 which cross a series of slits 14. Each of these slits 13 and 14 communicate with the interior and exterior of one of the cavities or chambers 4 at 105 the rim engaging portion of the filler, and tongues 15 are thereby formed in normally juxtaposed relation to one another.

Although the casing and filler are united throughout and beyond the tread portion, as

- previously described, they are disunited throughout the length of the slits 13, to increase the flexibility of the portion of the tire through which the balls 3 are inserted.
- 5 It will be seen, however, that the rim engaging portion of the casing 10 coacts with the rim for securely holding the tongues 15 in their juxtaposed relation to one another, thereby providing an unbroken inner surface
- 10 at the joint between the casing 10 and filler 11.

Although I have described this embodiment of my invention very specifically, it is not intended to limit the invention to these 15 exact details of construction and arrangement, but changes may be made within the scope of the inventive ideas as implied and claimed.

What I claim as my invention is:

- 20 1. In a tire, a flexible casing, a resilient filler in the casing, said filler being provided with an annular series of alternating spherical cavities and partitions, and hollow resilient spherical members normally fitted respectively in said cavities, a wall of each of

said cavities being provided with slits crossing one another and communicating with the interior and exterior of said wall so as to provide normally juxtaposed tongues which can be separated to permit insertion and removal of one of the spherical members, said tongues being adapted to resume their normal relation by their inherent resiliency.

2. In a tire, a flexible casing, a resilient 35 filler in the casing, said filler being provided with an annular series of alternating spherical cavities and partitions, and hollow resili- 40 ent spherical members normally fitted respectively in said cavities, each of the opposite upright walls of each cavity being formed with slits that cross one another and communicate with the interior and exterior so as to provide normally juxtaposed tongues which can be separated to permit one of the spherical members to be inserted and removed, for the purpose specified.

In testimony whereof I have hereunto set my hand.

HARRY S. WILLIAMS.
